UNITED STATES PATENT OFFICE.

PAULUS J. A. VAN DEINSE, OF GREENVILLE, MICHIGAN.

HOLLOW BLAST GRATE BAR.

Application filed October 31, 1922. Serial No. 598,162.

To all whom it may concern:

Be it known that I, PAULUS J. A. VAN DEINSE, a citizen of the United States, residing at Greenville, in the county of Mont-
5 calm and State of Michigan, have invented a new and useful Improvement in Hollow Blast Grate Bars, of which the following is a specification.

This invention relates to improvements in 10 hollow blast grates and particularly to the tuyères thereof.

The invention is particularly applicable to hollow blast grate bars employed in furnaces for burning sawdust, wood refuse, 15 sugar cane refuse, rice chaff and other similar fuels.

The general objects of the invention are to provide improved tuyères which will deliver a maximum volume of the blast to the 20 furnace, which will have no effect of weakening the grate bars, and which will not permit the fuel or ashes to accumulate in the chamber of the hollow grate bar.

Other objects will appear from the following description of two embodiments of 25 the invention.

In the accompanying drawing forming a part of this specification:

Figure 1 is a perspective view with parts 30 broken away showing a boiler furnace equipped with one form of the invention;

Figure 2 is a top plan view of one of the hollow grate bars;

Figure 3 is a vertical longitudinal section 35 on the line 3-3 of Figure 2;

Figure 4 is a vertical transverse section on the line 4-4 of Figure 2;

Figure 5 is a side elevation of one of the tuyère parts;

Figure 6 is a bottom plan view of the same;

Figure 7 is a side elevation of the tuyère element which is complementary to the part shown in Figure 5;

Figure 8 is bottom plan view of the same;

Figure 9 is a sectional view on the line 9-9 of Figures 6 and 8, the two parts being shown assembled;

Figure 10 is a similar view on the line 10-10;

Figure 11 is a similar view on the line 11-11;

Figure 12 is a cross section on the line 12-12 of Figure 6;

Figure 13 is a cross section on the line 13-13 of Figure 6;

Figures 14 and 15 are perspective views of the two parts of a modified tuyère; and

Figure 16 is a perspective view of a portion of a hollow blast grate bar equipped 60 with the tuyère parts illustrated in Figures 14 and 15.

Referring more specifically to the preferred embodiments of the invention shown in the drawing for illustrative purposes, and first particularly to Figure 1, the boiler furnace 16 is provided with a grate including ordinary draft bars 17 alternating with hollow blast grate bars 18 as shown, the grate bars extending from front to rear of the 70 fire box. Associated with the furnace is a blower 19, driven by any suitable means, whose outlet is joined to an elbow 20. The elbow 20 is connected with a pipe section 21, and to the other end of the pipe section 75 is joined a T consisting of a horizontal part 22 and a vertical part or nipple, the latter receiving the lower end of a vertical pipe 23. Several pipe sections 21 and T's 22 are joined in alternation to form a 80 delivery pipe for the blast extending transversely of the furnace beneath the grate, as shown. The upper end of each vertical pipe 23 is connected with one of the hollow blast 85 grate bars so that the blast from the blower 19 is distributed uniformly to all the grate bars 18. A gate valve or slide 24 provides convenient means for controlling the blast. The arrangement of parts so far described 90 is well known and forms no part of my invention.

The construction of the hollow blast grate bars 18 is best understood by reference to Figures 2, 3 and 4. In Figures 2 and 3 the front end of the grate bar 18 is at the left. 95 Each of the grate bars is provided with a plurality of circular openings of equal size whereby seats for the tuyère parts are provided, each of said seats including a sloping or inclined annular surface 25 and a flat horizontal circular ledge 26. The interior of the grate bar is hollow as indicated at 27, and the vertical pipes 23 are joined to depending coupling members 28 preferably integral with the grate bars, so that the blast from the fan passes through the chamber 27 and out through the tuyère openings. Preferably at the forward end of each grate bar 18 and upon the lower side thereof a blow-out passage 29 is provided, which is controlled by a slide 30, whereby any dirt or refuse collecting in the 100 105 110

2
chamber 27 may be blown out from time to time.

Supported by the surfaces 25 and 26 of the grate bar are annular tuyère elements 31, 5 each of which in turn carries a tuyère element 32, the two elements 31 and 32 together making up a duplex tuyère unit whose construction is one of the principal features of my invention. For a clear understanding of the duplex tuyère unit, Figures 5 to 13 inclusive should be referred to. The annular outer tuyère member 31, best shown in Figures 5 and 6, is preferably made of a single piece of cast iron or similar material. At the upper part of the member 31 is an annular beveled surface, the angle of which preferably corresponds with the angle or slope of the seats 25 provided in the grate bar. At intervals 10 about the periphery of the member 31 radial projections 35 and 36 are provided, and the outer end surfaces of all the radial projections are curved longitudinally in conformity with the annular shape of the tuyère member and are beveled transversely, so that the members 31 are supported within the holes provided in the grate bars preferably having their upper surfaces somewhat below the upper surface of the grate 15 bar. The radial projections 35 and 36 are preferably arranged in alternation and spaced equally about the periphery of the member 31. Each projection 36 has a seating extension 37 integral therewith and depending therefrom. Preferably the width of the projections 36, combined with the width of the extensions 37, is somewhat less than the depth of the seats provided by the bevel surfaces 25, so that when the lower 20 ends of the extensions 37 rest upon the ledge 26, as shown in Figure 11, the upper surface of the tuyère is slightly lower than the upper surface of the grate bar. Beneath some of the projections 35, 36, a wing 25 38 is provided, and the wings 38 extend to the bottom of the tuyère member 31 and have their outer surfaces curved so that the wings may extend through the holes provided in the upper sides of the grate 30 bars, as seen in Figures 12 and 13. The object of the wings is to prevent displacement of the tuyère parts during the firing operation.

From what has been described, it will be 55 understood that the compressed air delivered to the interior 27 of the hollow grate bars may issue from the passageways provided between adjacent radial projections 35 and 36; and as will be understood from Figure 60 2, these passageways are relatively long and narrow, so that there is practically no tendency during the operation of the furnace for the fuel to clog the openings to prevent the blast of air from issuing out of 65 the passageways.

The central opening 39 of each annular tuyère member 31 has a beveled seat 40 and a circular ledge 41 corresponding respectively to the seating surfaces 25 and 26 of the grate bar. The tuyère member 32 is preferably made of cast iron and has integral radial projections 42 and 43 analogous respectively to the projections 35 and 36 previously described. Each projection 43 has a seating extension 43^a; and wings 44 project radially from the member 32 and are passed through the lower part of the hole or bore provided in each annular tuyère member 31 so as to prevent displacement of member 32. The tuyère element 32 is supported by engagement of the seating extensions 43^a with the ledge 41, so that its upper surface is preferably somewhat below the upper surface of tuyère member 31, which in turn is preferably somewhat lower than the upper surface of the hollow grate bar. A plurality of narrow passageways for the blast of air are provided between adjacent projections 42 and 43. The lower part of the inner tuyère member 32 is enlarged and made of somewhat bulbous shape as shown and depends below the outer tuyère member which adds to the weight and prevents displacement. In other words, the weight of the inner member assists in holding the outer member in place.

The improved duplex tuyère of my invention has two circular sets or series of holes or passageways for the air blast arranged concentrically. Obviously the blast issuing from each tuyère may be varied by substituting tuyère elements having a greater or lesser number of passages than those shown in the drawing. It is also clear that the exact shape and size of the air 105 passages may be varied in different tuyère units.

Each of the grate bars 18 supports any desired number of the tuyères, all of which are alike except that at the front end of each grate bar the foremost tuyères consisting of parts 33 and 34 are so shaped that the blast is directed through only the rear half of the castings, as will be understood from Figure 2, so that no part of the fire is forced against the furnace door.

A modified form of the invention is shown in Figures 14, 15 and 16 wherein the hollow grate bar 18^a is provided with a plurality of rectangular openings or perforations having inclined tuyère seats 45. The outer tuyère element 46 has a central rectangular slanting or beveled seat 47 designed to support the inner tuyère member 50 shown separately in Figure 15. At regular intervals about the four sides of the outer member 46, passageways 48, 49 are provided so that the blast of air from the interior of the grate bar may pass upwardly into the fire box of the furnace. The in-

terior tuyère element 50 also has passage-ways 52, 53 for the air blast. The constructions of Figures 5 to 13 inclusive and Figures 14 to 16 inclusive are in general the same, and the results obtained by the use of either construction are similar, the essential difference being that in one case the tuyère members are circular while in the other case they are rectangular.

Some of the advantages of the invention are that ashes and fine particles of fuel entering the tuyère settle only upon the ledges 26, 41, from which they are quickly expelled by the blast. Again, if the plant remains idle for any length of time, rust and scale will gather in the outlets of an ordinary blast grate bar and obstruct them; while with my invention the tuyères can be readily removed, the outlets cleaned and the tuyères replaced. Sometimes it is discovered that the grate bar outlets originally provided are too large or too small, due either to an error in calculation or to a change in fuel. My invention provides means whereby the size of the outlets may be increased or reduced temporarily or permanently to any extent desired and as often as may be necessary.

The tuyères of my invention being held in place solely by their own weight, they are readily removed to give access to the interior of the grate bar. For this reason and the further reason that a minimum of ashes, etc., finds its way into the interior of the bar, the blow-out in the front end thereof need be used only on very rare occasions, or may be dispensed with altogether. On the other hand, when wet sawdust or other matter containing a large percentage of moisture is burned on a hollow blast grate bar without gravity tuyères, the ashes entering the interior of the bar becomes moist and cakes, requiring it to be dug out manually—an operation of considerable difficulty and taking considerable time, as the bar must usually be removed from the furnace for the purpose.

The invention greatly increases the area of the blast outlets without adding to the number of the tuyère seats in the top of the grate bar, which would weaken the grate bar and permit it to sag, and at the same time the openings do not become obstructed by the fuel, as has already been pointed out.

While I have described two preferred embodiments of the invention, it will be understood that many changes may be made from the above, without departing from my invention, which is best defined in the following claims.

In practice, I may combine a circular tuyère member with a rectangular tuyère member by arranging the circular member either on the outside or within the rectangular member, thereby making four differ-

ent combinations; or I may make either tuyère member of any other desired shape.

What is claimed is:

1. A hollow blast grate bar having an opening on its upper side leading from the interior thereof, in combination with a tuyère adapted to be seated in and partially close said opening, said tuyère being made up of two elements having air passages, one element seated on the wall of said opening and the other element seated on the first-mentioned element so that its upper surface is below the surface of the grate bar, both elements being held in position by gravity.

2. A hollow blast grate bar having an opening on its upper side communicating with its interior, and a tuyère seated upon the grate bar at said opening with its upper flat surface disposed lower than the upper surface of the grate bar, said tuyère being held in position solely by gravity, and comprising two tuyère elements, one of which seats the other and is in turn seated within said opening.

3. In combination with a hollow blast grate bar having an opening providing a seat in one side, a tuyère element having a plurality of passages for air as well as a central aperture, said aperture providing a seat for a second tuyère element likewise provided with air passages, both seats and the seating surfaces of both elements being formed similarly, and the second tuyère element being provided with a depending weighted enlargement to hold both tuyère elements on their seats solely by gravity.

4. A hollow blast grate bar having an opening on its upper side leading from the interior thereof, in combination with a tuyère adapted to be seated in and partially close said opening, said tuyère being made up of two elements each having air passages, the outer element being seated on the wall of said opening below the upper surface of the grate bar, and the inner element being seated on the first-mentioned element below the upper surface of the outer element and provided with a weighted enlargement depending below the other element, whereby both elements are held in position by gravity.

5. A hollow blast grate bar having an opening in its upper wall leading from the interior thereof, said opening having an inclined surface and a flat horizontal ledge below the top face of said upper wall, and a tuyère element fitted in said opening having a series of spaced projections at the periphery engaging said inclined surface, air passages being provided between adjacent projections certain of the projections having a depending seating extension to rest upon the ledge, wings provided on certain of the projections and extending to the

bottom of the tuyère element, said tuyère element having a central opening with a beveled seat and a flat horizontal ledge below the top face thereof, and a second tuyère element fitted in said central opening having radial projections at the periphery engaging said beveled seat, air passages being provided between adjacent projections, certain of said projections having extensions resting on the last-mentioned ledge.

6. A hollow blast grate bar having an opening in its upper wall leading from the interior thereof, said opening having an inclined surface and a flat horizontal ledge below the top face of said upper wall, and a tuyère element fitted in said opening having a series of spaced projections at the periphery engaging said inclined surface, air passages being provided between adjacent projections, certain of the projections hav-

ing a depending seating extension to rest upon the ledge, wings provided on certain of the projections and extending to the bottom of the tuyère element, said tuyère element having a central opening with a beveled seat and a flat horizontal ledge below the top face thereof, and a second tuyère element fitted in said central opening having radial projections at the periphery engaging said beveled seat, air passages being provided between adjacent projections certain of said projections having extensions resting on the last-mentioned ledge, the second tuyère element being weighted and serving to hold both elements onto their seats solely by gravity.

In testimony that I claim the foregoing as my own, I have hereto affixed my signature.

PAULUS J. A. VAN DEINSE.
